UNITED STATES PATENT OFFICE.

ANTONY STRUKELL, OF BROOKLYN, NEW YORK, ASSIGNOR OF ONE-FOURTH TO
HARRY B. DODS, OF BROOKLYN, NEW YORK.

THREAD-CUTTING MACHINE.

1,354,078.

Specification of Letters Patent. Patented Sept. 28, 1920.

Application filed December 4, 1919. Serial No. 342,363.

To all whom it may concern:

Be it known that I, ANTONY STRUKELL, a citizen of Austria, residing at Brooklyn, Kings county, State of New York, have invented certain new and useful Improvements in Thread-Cutting Machines, of which the following is a full, clear, and exact description.

This invention relates to improvements in thread cutting machines. One of the objects of this invention is to provide a machine to automatically thread fountain pen barrels to receive a cap. My improved device is designed to automatically cut threads at the open end of a fountain pen barrel; that is to say, the end which receives the pen section and cap to cover the pen section. To completely carry out the object of my invention, I have arranged the device to automatically stop after a predetermined number of threads have been cut. My improved automatic thread cutting machine will greatly reduce the cost of manufacture of fountain pen barrels, and will, furthermore, produce a clean cut thread, either single or multiple, as may be desired.

I will now proceed to describe my invention in detail, the novel features of which will be pointed out in the appended claims, reference being had to the accompanying drawings, forming part hereof, wherein:

Figure 1 is a top plan view of an embodiment of my invention;

Fig. 2 is an enlarged fragmentary sectional view, illustrating the die, a portion of a fountain pen barrel, and supporting spindle therefor;

Fig. 3 is a face view of the die;

Fig. 4 is a side elevation of the device;

Fig. 5 is an enlarged longitudinal sectional view of a portion of the machine, the die being shown in elevation;

Fig. 6 is an enlarged cross-sectional view, the section being taken on a line 6-6 in Fig. 4;

Fig. 7 is a fragmentary sectional view of the spindle and therein contained threaded sleeve for operating the barrel spindle; and

Fig. 8 is an enlarged elevation of a fountain pen barrel, broken away, a cap being illustrated in section.

While my improved device may be embodied in various forms, I have herein illustrated a simple construction consisting of a standard member 9, which supports a ro-

tatable hollow spindle 10, said spindle being supported by the bearing members 11. The bearing members 11 may be provided with bushings 12, made of phospho-bronze or other suitable material. The spindle 10 has 60 tightly secured thereto by means of a set-screw 14, a belt-pulley 15, by which means, and a belt 16, the pulley 15 is rotated. On each side of the pulley 15 I place a loose pulley 17, that is to say, on each side of the 65 pulley 15 I place a loose pulley, one of which, in this instance the one on the left, is engaged by a cross belt 18, for the purpose of reversing the spindle 10, after said spindle has been caused to cease rotating by 70 the shifting of the belt 16 from the tight pulley 15 to the loose pulley 17, at the right of the said pulley 15 (see dotted lines in Fig. 1).

One end of the spindle 10 carries a die 19 75 provided with cutters or tools 20, 21 and 22. The cutters referred to are held between a cap 23 and the body of the die, by means of set-screws 24, the cap being held in the body of the die by screws 25. The die 19 carries 80 a tapered shank 26, which fits the tapered counter bore 27 of the spindle 10. The die is frictionally held by the spindle 10 and is removable therefrom. As can be seen in Fig. 2, the cutters 20 to 22, inclusive, project into a counter-bore 28 in the die 19, said counter bore being deep enough to enable the cutters to cut threads upon the adjacent end of a fountain pen barrel, indicated by 29, to the desired extent. The counter-bore 90 28 will be deep enough to permit of the cutting of threads to an extent greater than will be needed for the application of a cap, but it is within the scope of my invention to provide a die having a counter-bore, such as 95 28, deep enough to cut threads to any desired extent. The open end 30 of the cap 29 is supported by a longitudinally movable rod 31, having a conical end 32, upon which the adjacent end of the barrel is placed. Intermediate its ends, the rod 31 is provided with threads 32 to engage a threaded sleeve 33 (see Figs. 5 and 7), secured within the hollow spindle 10 by set screws 34. The sleeve 33 will be removable as well as the rod or 100 barrel support 31, for the purpose of installing a rod and sleeve having threads of a different pitch. The rod 31, at the end opposite to the pointed end, will be secured to a cross-head 35 by a set screw 36. The cross- 110

head 35 is carried by longitudinally movable rods 37, slidably supported by bearings 38, projecting from the bearing members 11. The opposite end of each rod 37 is secured 5 to a cross-head 39, carrying a chuck 40. The chuck 40 is slidably retained by the cross-head 39, and may be moved toward or away from the die 19 in order to mount a barrel for cutting or to remove same after 10 it has been cut. The chuck 40 carries a pin 41, which engages a slot 42 in the hub 43 of the cross-head 39, when said chuck is pushed all the way in to engage the end 43 of a barrel to be cut. The pin 42 prevents 15 the chuck from rotating while the barrel is being cut. The end 43 of the barrel 29 will tightly fit the socket 44 in the chuck 40, and will not rotate therein.

As I desire to cause the cutters to cease operating after a predetermined number of 20 threads have been cut, I provide the rods 37 with adjustable stops, one of said stops being indicated by 45, the other by 46. As can be seen in Fig. 1, the stop 46 is in the nature 25 of a sleeve, which carries a fork 47, engaging the belt 16 for the tight pulley 15. The stops are secured in adjusted positions by set 30 screws 48. To shift the cross-belt 18, I provide a pivoted fork 49, operable (in this instance) by means of a pedal 50. The belt 35 18 will normally engage the loose pulley 17 at the left of the pulley 15, and will be shifted to the pulley 15 when a reversal of the spindle 10 is desired. To maintain the rod or barrel support 31 in its extreme position, to the left, in order to keep the threads 40 32 on said rod out of mesh with the threads in the sleeve 33, when the machine is not in operation to cut threads, I employ a spring 45 51, which connects the stop 46 and one of the bearings 38 (see Fig. 1). It may here be stated that cutting tools 20 to 22, inclusive, are removable, in order that they may 50 be sharpened. In order to position the cutting edge of the tool in proper relationship with the outer surface of the wall of the barrel 29, I may employ any suitable tool, such for instance as a tapered lug; as a tool for this purpose has no bearing upon the operation of the machine other than that of setting the tools, a description thereof is thought to be superfluous.

I will now proceed to describe the operation of the machine.

To cut threads upon a fountain pen barrel, the chuck 40 will be moved in the direction of the arrow 52 (Fig. 1), far enough 55 to permit of the insertion of the closed end of the barrel into the socket 44. After the 60 barrel has been placed in the socket 44, the chuck 40 and the barrel will be moved in the direction of the arrow 53, to cause the open end of the barrel to engage the conical end 32 of the support or rod 31, as indicated in Fig. 2. During the above described

operation, the spindle 10 may be in operation under the influence of the belt 16. After the barrel has been placed upon the rod 31, as above described, the pin 41 will be in engagement with the slot 42, therefore, 70 the chuck 40 and barrel 29 will be held against rotation. The next step in the operation of threading the barrel will be to force the carriage A, which is made up of the rods 37, cross-heads 35 and 39, and the 75 rod 31, in the direction of the arrow 54, to cause the threads 32 on the rod 31, to engage the bushing 33. It will be remembered that the threads on the rod 31 are kept out of engagement with the threads of 80 the bushing 33, excepting while the threads are being cut. After the threads on the rod have been caused to engage the bushing 33, which will be in motion or rotating, the rod 31 will be drawn in the direction of the 85 arrow 54, Fig. 1, thereby causing the carriage A to move in a corresponding direction. A continued movement in the direction indicated will cause the barrel 29 to become engaged by the cutters 20 to 22, inclusive, and a continued rotation of the die, which is carried by the rotating spindle, will cut threads in the barrel 29. The carriage A will continue to move to the right, in this instance, until the stops 45 and 46 90 95 contact with the bearing members 38. During the movement of the carriage in the direction above indicated, the belt 16 will be caused to travel from the tight pulley 15 toward the loose pulley 17 at the right of 100 said pulley 15. About the time that the stops 45 and 46 contact with the bearing members 38, the belt 16 will have cleared the tight pulley 15, and the spindle 10 will stop.

To reverse the spindle 10 to cause the barrel 29 to move toward the left, the pedal 50 will be depressed causing the cross-belt 18 to move onto the tight pulley 15, after which the spindle 10 will be reversed and cause the carriage A to move to the right until the 110 threads on the rod 31 clear the threads of the bushing 33. As soon as the last thread clears the bushing 33, the spring 51 will move the carriage slightly farther toward the left, thereby causing the last thread on 115 the rod to completely clear the bushing 33. As the fork 47 is carried by the stop 46, the belt 16 and face 56 of the stop 46 will always be maintained in the same relationship one to the other, consequently whenever the 120 stop 46 is shifted the belt 16 will be shifted a corresponding amount; hence, whenever stop 46 comes in contact with the bearing 38, the belt 16 will always clear the tight pulley 15, and the danger of having the 125 stop, or a stop, coming in contact with its abutment before the driving belt leaves the driving pulley is obviated. Should the stop come in contact with its abutment before the driving belt leaves the driving pulley, the 130

threads would be destroyed; that is to say, the threads at the end of the threaded portion of the barrel. To thread a cap, a chuck (not shown) would be substituted for the 5 die 19, and a tap placed in the chuck. In this instance the cap would be held by the chuck 40, the same as a barrel.

What I claim and desire to secure by Letters Patent is:—

10 1. In a thread cutting machine, a longitudinally movable carrier to receive the article to be threaded, a chuck in line therewith to coöperate with said carrier to hold the said article while the threads are being 15 cut, said chuck being movable with said carrier, rotatable cutting tools adjacent the carrier, means to rotate the cutting tools, and means to automatically cause the tools to cease operating after a predetermined 20 number of threads have been cut.

2. In a thread cutting machine, a longitudinally movable carrier to receive the article to be threaded, a chuck in line therewith to coöperate with said carrier to hold 25 the said article while the threads are being cut, said chuck being movable with said carrier, rotatable cutting tools adjacent the carrier, means to rotate the cutting tools, means to automatically cause the tools to 30 cease operating after a predetermined number of threads have been cut, and means to move the carrier in a direction opposite to the direction imparted thereto while the threads are being cut, after the said threads 35 have been cut.

3. In a thread cutting device, a carrier, a support therefor, threads carried thereby, a threaded element to engage the threads on said carrier, means to rotate the threaded 40 element to move said carrier longitudinally of its support, a rotatable cutting tool adjacent the carrier, and a chuck coöperating with said carrier to support the article to be threaded.

45 4. In a thread cutting device, a longitudinally movable carriage, supports therefor, a carrier supported at one end by one end of said carriage, a chuck supported by the carriage at the other end thereof, said chuck aligning with said carrier, a rotatable cutting tool adjacent said carrier arranged to 50 thread articles held by said chuck and carrier, and means to move the carriage longitudinally of its supports, to cause the article 55 to be threaded to engage said tool.

5. In a thread cutting machine, a rotatable hollow spindle, a threaded bushing within the spindle, a longitudinally movable carrier within the spindle projecting from 60 one end thereof, and arranged to receive one end of the article to be threaded, threads carried by the carriage, to be engaged by the threaded bushing, a die carried by said hollow spindle located adjacent the projecting 65 end of said carrier and surrounding same,

means to rotate the spindle, and manual means to move the carrier to cause the threads thereon to engage the said threaded bushing.

6. In a thread cutting machine, a rotatable 70 hollow spindle, a threaded bushing within the spindle, a longitudinally movable carrier within the spindle projecting from one end thereof, and arranged to receive one end of the article to be threaded, threads carried 75 by the carriage, to be engaged by the threaded bushing, a die carried by said hollow spindle located adjacent the projecting end of said carrier and surrounding same, means to rotate the spindle, manual means to move 80 the carrier to cause the threads thereon to engage the said threaded bushing, and means to cause the hollow spindle to cease rotating after a predetermined number of threads have been cut. 85

7. In a thread cutting machine, a rotatable spindle, a tight pulley carried thereby, a loose pulley at each side of the tight pulley, a belt movable from the tight pulley to one of the loose pulleys and vice versa, 90 a cross-belt normally engaging the other loose pulley and movable to engage the tight pulley, a threaded bushing within the hollow spindle, a longitudinally movable carrier within the spindle and projecting from one 95 end thereof, threads carried by the carrier to be engaged by the threaded bushing, said carrier being arranged to retain the article to be threaded, a die carried by the spindle located adjacent the projecting end of said 100 carrier, means to arrest the movement of the carrier after a predetermined number of threads have been cut, means to shift the belt from the tight pulley to the coöperating loose pulley during the cutting of the 105 threads to cause the hollow spindle to cease rotating when said carrier comes to rest, and means to shift the cross-belt from its loose pulley to the tight pulley to reverse the movement of the hollow spindle. 110

8. A device for cutting threads in the outer surface of tubular articles, a longitudinally movable carrier having a conical end to be inserted into one end of the hollow article, a chuck movable with said carrier to receive the opposite end of said article, a rotatable element to actuate or move said carrier and coöperating chuck, a rotatable die arranged to cut threads in the wall of said tubular article, during the longitudinal 115 movement thereof, and means to arrest the movement of said carrier after a predetermined number of threads have been cut. 120

Signed at New York city, N. Y., this 2nd day of December, 1919.

ANTONY STRUKELL.
